DEVICE FOR DEMONSTRATING ENGRAVING ON SILVERWARE

Nelson Ewing, Hampton, N.H., and Frank M. Hargraves, Merrimac, Mass., assignors to Towle Manufacturing Company, Newburyport, Mass., a corporation of Massachusetts

Filed July 20, 1961, Ser. No. 125,435
5 Claims. (Cl. 35—49)

This invention pertains to demonstrating apparatus, more especially to apparatus designed to assist the purchaser of flatware table silver in selecting a pleasing style of letter for the marking or engraving of the pieces purchased.

Various styles of letter are used in the marking of silverware, for example script, block, Gothic, Old English, and so forth, as well as modifications of conventional styles, designed especially for silverware. However, it is difficult for many persons, merely by looking at a printed chart, or pictures illustrating the use of different style of letter, to select the one which will be most satisfactory when actually engraved upon a silver piece of the pattern purchased—sometimes with disappointing results. Even though the merchant may have sample spoons, for example, actually engraved with different styles of letter to assist the purchaser in making a selection, there is no certainty, unless one of these marked sample spoons be of the same pattern which is being purchased, that the style of letter which may look well on the sample will be as pleasing when applied to a different pattern.

The present invention has for its objects the provision of simple apparatus whereby it is made readily possible to exhibit to a purchaser the actual appearance of various styles of letter as applied to the particular silver pattern in which the purchaser is interested. A further object is to provide apparatus whereby it is readily possible to demonstrate the appearance of two or three letters arranged as a group to form a monogram upon a selected piece of silver. A further object is to provide apparatus of the above type of simple construction which may readily be manipulated in giving the desired demonstration, either by the merchant or the would-be purchaser: which is durable; occupies but little space; and which is of a character such that it may be placed upon the sales counter or table without damage to the latter and which is of pleasing appearance and inexpensive to manufacture.

Other and further objects and advantages of the invention will be pointed out in the following more detailed description and by reference to the accompanying drawings wherein:

FIG. 1 is a plan view, with parts broken away, showing one embodiment of the present invention and illustrating how it is used in demonstrating the appearance of a group of letters as they would be applied to the handle, for example, of a silver spoon;

FIG. 2 is an edge view of the device of FIG. 1;

FIG. 3 is a section to larger scale than FIG. 1, on line 3—3 of FIG. 1;

FIG. 4 is a fragmentary bottom view, to smaller scale, of the cover of the device;

FIG. 5 is a fragmentary section on the line 5—5 of FIG. 1, showing the manner in which the transparent alphabet-carrier overlies the article which is to be engraved during the demonstration;

FIG. 6 is a fragmentary plan view showing three concentric alphabet carriers having thereon letters so styled that when letters of the three carriers are juxtaposed they form a pleasingly designed monogram; and

FIG. 7 is a plan view, to smaller scale than FIG. 1, illustrating an interchangeable article support, which may

2

constitute a removable portion of the base of the device, thereby to adapt it to various styles of article.

Referring to the drawings, the character A (FIG. 1) designates the apparatus as a whole, this apparatus comprising the base 10 which is here shown, for example, as circular in plan and which may be made of any suitable rigid material, for example wood or a plastic. The apparatus also comprises the cover member 11 (FIGS. 1, 2 and 4) which may be of the same material as the base

10 or of a different material, and which is also circular and of the same outside diameter as the base, and which is here shown as secured in assembled relation to the base by screws S. However, other means of uniting the cover and base, for example, quick-acting clamps or spring clips 15 may be employed within the scope of the invention.

The base 10 has the annular, flat, horizontal upper surface 12 (FIG. 3) from whose center rises the cylindrical boss or pivot member 13 which may or may not be integral with the lower portion of the base as preferred.

20 The cover 11 is provided at its underside (FIG. 4) with a flat, horizontal marginal rib 11a (FIG. 4) which rests upon the surface 12 of the base when the parts are assembled—the cover having the central bore 14 (FIG. 4) which receives the boss 13 of the base. The boss serves 25 to position the cover relatively to the base and also as a pivot about which the alphabet-carriers, hereinafter referred to, may rotate. As here shown, the cover 11 has the central upstanding boss 15 (FIG. 2) which serves to provide sufficient thickness of material for the formation 30 of the bore 14 without adding unduly to the weight of the device.

The base 10 is provided with a radial trough 16 which extends inwardly and preferably into the central boss 13, this trough being designed to position that part, for example the handle H, of a piece of table flatware in the performance of the demonstration. As shown in FIG. 1 this trough 16 is holding, in position for inspection, the handle H of a spoon—the particular pattern of handle shown being one which tapers gradually toward its tip. The trough 16 is of a depth such that when the handle H is placed in the trough, the upper surface of the handle, which is that to which the engraved lettering is to be applied, projects slightly above the flat surface 12 of the base. As shown, the trough 16 is formed in the material 40 of the base, proper, but it is contemplated that the trough may be formed in a removable portion of the base, for instance a segmental portion 10x (FIG. 7) so that by providing a plurality of such segmental portions, having troughs of different shape, the device may readily be set 45 up to demonstrate with widely different silver patterns.

The cover 11 is provided with an open slot 17 (FIG. 4) which, when the cover and base are assembled, registers with the trough 16. However, this slot in the cover is 50 of greater width than that of the trough and has sidewalls 55 18 which curve downwardly, preferably with convex surfaces, to their intersections with the undersurface of the cover.

As may be noted from inspection of FIGS. 3 and 4, that portion of the undersurface of the cover which lies 60 between the flat rim 11a of the cover and the boss 13, is spaced from the surface 12 of the base when the parts are assembled, so as to provide a chamber C (FIG. 3) beneath this part of the cover—this chamber being annular and concentric with the boss 13.

65 In accordance with the present invention one or more alphabet carriers are arranged within this chamber D. Desirably, as here shown, three such alphabet carriers 22a, 22b and 22c are provided. Each of these carriers is an annulus of flexible transparent material, for example cellophane or some other tough, flexible synthetic resin, each annulus having a central opening of a size to receive 70

the boss 13 with a turning fit, so that the boss 13 constitutes a fixed pivot about which each alphabet carrier may turn. These carriers 22a, 22b and 22c, as shown in FIG. 1 are of progressively greater outside diameters so that when the parts are assembled, as shown in FIGS. 1 and 3, a marginal portion of each of these carriers is exposed to view within the slot 17 of the cover. Upon the margin of each of these carriers is arranged an alphabet consisting of circumferentially spaced letters of a predetermined style, for instance block letters, Gothic letters, script letters, etc.; the letters on all of the several carriers being of the same style. As shown in FIG. 1, for simplicity, these letters are shown as block letters. Desirably between the letter Z and the letter A of each alphabet there is left a blank space of a width at least as great as one letter.

The cover is provided with a plurality of parallel slots 20a, 20b and 20c (FIG. 4) corresponding in number to the number of alphabet carriers and within these slots there are arranged drive rollers 21a, 21b and 21c, respectively, the several rollers being mounted to turn upon a pin 22 which is driven into or otherwise fixed within the substance of the cover. The drive rolls are of such diameter and the axis of the pin 22 is so located that the lower peripheral portions of the respective rollers contact the exposed margins of the several alphabet-carriers, respectively, while the upper portions of the respective rolls are exposed above the upper surface of the cover. These rolls are desirably of resilient material and elastically press down upon the margins of the respective alphabet-carriers, but in any event they are so devised as to provide friction surfaces contacting the carriers. By turning one of the rolls by hand, where it is exposed at the exterior of the cover, the corresponding alphabet-carrier will be rotated about the boss 13 as a pivot, so that it is thus possible to cause any selected letter on any selected carrier to overlie the trough 16 in the base.

In the use of this device for demonstrating the approximate appearance of an engraved article, that portion of the article, for example the handle H of a spoon, is inserted in the slot 16 in the base and, in so doing, is slipped beneath the margins of the several alphabet carriers 22a, 22b and 22c as shown in FIG. 5. Since these carriers are transparent, the handle of the spoon may be seen clearly beneath the carriers (FIG. 1). Because the trough 16 is so dimensioned that a portion of the article, which is to be engraved, slightly projects above the horizontal surface 12 of the base upon which the several carriers rest, the insertion of the article in the trough tensions the carriers where they extend across the trough between the parallel edges of the slot 17 in the cover, so that the carriers closely contact the article.

With the parts in this position the drive rolls may be turned so as to bring any selected combination of letters to overlie the handle H of the spoon so that the letters on the transparent carrier appear as though actually on the handle. Thus the observer is able clearly to appreciate the approximate appearance of the article when marked with letters of the particular style thus demonstrated.

It is contemplated that the merchant may provide himself with a plurality of these devices, each having alphabet characters whose letters are in accordance with one of the most popular styles. On the other hand, it is readily possible by removing the cover from the base to substitute alphabet carriers having letters of any desired style so that merely by carrying in stock sets of alphabet carriers with letters of different styles, the merchant is able to exhibit and demonstrate to the purchaser a wide selection of lettering.

Since each of the alphabet carriers is provided with a blank space between certain letters, it is possible, if but a single letter is to be engraved upon the article, to turn the carriers so that blanks appear where no letters are desired, and since the carriers are at different radial dis-

tances inwardly from the edge of the device, it may readily be demonstrated as to the location longitudinally of the part to be engraved at which a single letter would provide the most pleasing appearance.

As illustrated in FIG. 6, it is possible, by providing the several carriers 23a, 23b and 23c with specially designed letters, to form a monogram such as would ordinarily require careful custom design and application. Thus, as shown in FIG. 6 the letters A, B and C of the three carriers are so shaped that, when assembled as shown, they form a monogram M of unitary appearance and pleasing design. It will be obvious that the other letters of the same alphabet would, in the same way, be shaped, so that when associated to form the desired combination, a monogram of similar design would result.

As above suggested, since the shapes of spoon handles of different patterns vary widely, it may be desirable to form the article receiving trough 16 in a part of the base 10 which is removable and interchangeable with others, the several parts having troughs of different shape. Thus as indicated in FIG. 7, the part 10a of the base 10 wherein the trough 16 is formed may be a segment-shaped part which slides into a suitably shaped recess in the base.

While one desirable embodiment of the invention has herein been illustrated and described by way of example, it is to be understood that the invention is broadly inclusive of any and all equivalents within the terms of the appended claims.

We claim:

1. Apparatus for use in demonstrating the approximate appearance of an article of table silver when engraved with a letter of a selected style, said apparatus comprising a support having a substantially flat, annular upper surface, a circular boss coaxial with said surface, an annular alphabet-carrier of transparent material having thereon the letters of the alphabet of a selected style, said carrier having a central opening for the reception of said boss, the latter constituting a pivot element about which the carrier may be rotated, the boss having, in its upper surface, a trough for holding the part of the article which is to be engraved, said trough being of a depth such that, when said part of the article is placed therein, the surface of the article which is to be engraved lies in a plane above said flat, annular surface of the support, a cover which overlies said support, the cover having a slot which registers with the trough through which the article is visible, means securing the cover to the support, the annular carrier spanning the trough and overlying that surface of the article which is to be engraved, and means for turning the carrier about said boss thereby to register any selected letter with the article, the means for rotating the annular carrier about the boss comprising a manually actuatable, friction roll whose periphery engages the annular carrier.

2. Apparatus for use in demonstrating the approximate appearance of an article of table silver when engraved with a letter of a selected style, said apparatus comprising a support having a substantially flat, annular upper surface, a circular boss coaxial with said surface, an annular alphabet-carrier of transparent material having thereon the letters of the alphabet of a selected style, said carrier having a central opening for the reception of said boss, the latter constituting a pivot element about which the carrier may be rotated, the boss having, in its upper surface, a trough for holding the part of the article which is to be engraved, said trough being of a depth such that, when said part of the article is placed therein, the surface of the article which is to be engraved lies in a plane above said flat, annular surface of the support, a cover which overlies said support, the cover having a slot which registers with the trough through which the article is visible, means securing the cover to the support, the annular carrier spanning the trough and overlying that surface of the article which is to be engraved, and means for turning the carrier about said boss thereby to register any selected letter with the article, a plurality of independent annular,

transparent, flexible alphabet-carriers arranged to rotate about said boss, the several carriers being of progressively greater outside diameters so that the outer margin of each respective carrier is exposed to view, each carrier having on its exposed margin an alphabet consisting of letters of the selected style, and means for rotating each individual carrier about said boss whereby any selected letter on any carrier may be arranged to overlie an article resting in said trough.

3. Apparatus for use in demonstrating the approximate appearance of an article of table silver when engraved with a letter of a selected style, said apparatus comprising a support having a substantially flat, annular upper surface, a circular boss coaxial with said surface, an annular alphabet-carrier of transparent material having thereon the letters of the alphabet of a selected style, said carrier having a central opening for the reception of said boss, the latter constituting a pivot element about which the carrier may be rotated, the boss having, in its upper surface, a trough for holding the part of the article which is to be engraved, said trough being of a depth such that, when said part of the article is placed therein, the surface of the article which is to be engraved lies in a plane above said flat, annular surface of the support, a cover which overlies said support, the cover having a slot which registers with the trough through which the article is visible, means securing the cover to the support, the annular carrier spanning the trough and overlying that surface of the article which is to be engraved, and means for turning the carrier about said boss thereby to register any selected letter with the article, the cover having a plurality of slots each overlying the exposed margin of one of said carriers, respectively, a drive roll in each slot, pivot means for the several drive rolls, each drive roll being of resilient material and of a diameter such that its periphery frictionally engages the margin of a corresponding carrier.

4. Apparatus for use in demonstrating the approximate appearance of an article of table silver when engraved with a letter of a selected style, said apparatus comprising a support having a substantially flat, annular upper surface, a circular boss coaxial with said surface, an annular alphabet-carrier of transparent material having thereon the letters of the alphabet of a selected style, said carrier having a central opening for the reception of said boss, the latter constituting a pivot element about which the carrier may be rotated, the boss having, in its upper surface, a trough for holding the part of the article which is to be engraved, said trough being of a depth such that, when said part of the article is placed therein, the surface of the article which is to be engraved lies in a plane above said flat, annular surface of the support, a cover which overlies said support, the cover having a slot which

registers with the trough through which the article is visible, means securing the cover to the support, the annular carrier spanning the trough and overlying that surface of the article which is to be engraved, and means for turning the carrier about said boss thereby to register any selected letter with the article, the letters of the alphabet, carried by the several carriers, being of such configuration that when letters selected from the alphabets of the respective carriers are registered, concomitantly, with the article to be engraved, they so merge with each other as to form a monogram.

5. Apparatus for use in demonstrating the approximate appearance of an article of table silver when engraved with a letter of a selected style, said apparatus comprising a circular, rigid base having an upstanding central circular boss surrounded by a flat, horizontal, annular surface, a circular cover having at its underside a bore for the reception of said boss, means for uniting the cover to the base, the cover having an annular marginal rim at its underside which contacts said horizontal upper surface of the base and a vertically shallow, annular chamber between said annular marginal rim and its central bore, the horizontal surface of the base constituting the floor of said chamber, a plurality of transparent flexible alphabet-carriers of progressively increasing outside diameter arranged within said chamber, so as to turn about said boss as a pivot, the exposed margin of each respective carrier having thereon the letters of the alphabet, all of said letters being of a selected predetermined style, a plurality of drive rolls arranged within slots in the cover and whose peripheral surfaces frictionally engage the exposed margins of the respective carriers, the rolls being exposed at the exterior of the cover whereby they may be turned manually, thereby to rotate the carriers about said boss, the base having a radial trough in its upper surface for positioning that part of the article which is to be engraved, the trough being of a depth such that, when said part of the article is placed therein, said part projects above the plane of the horizontal upper surface of the base, the cover having a slot which registers with the trough in the base and through which the article is visible, the edges of said slot being operative to hold that part of each transparent carrier, which spans the trough, in taut engagement with the upper surface of the article resting in the trough.
